POOL FOR ELEMENTARY SWIMMING CLASSES

Claude W. Ahrens, West Highway 6,
Grinnell, Iowa 50112

Filed Apr. 6, 1973, Ser. No. 348,510

Term of patent 14 years

Int. Cl. D25—99

U.S. Cl. D13—1 G

FIG. 1 is a front perspective view of the pool for elementary swimming classes showing my new design;

FIG. 2 is a top plan view;

FIG. 3 is a rear view; and

FIG. 4 is an end view of the pool for elementary swimming classes looking at the end thereof opposite the end shown in FIG. 1.

I claim:

The ornamental design for a pool for elementary swimming classes, substantially as shown.
